FLUIDIZED CONVERSION AND COKING OF
HEAVY PETROLEUMSFrederick W. Leffer, Riverside, Ill., assignor to
Universal Oil Products Company, Chicago, Ill.,
a corporation of Delaware

Application December 10, 1949, Serial No. 132,309

16 Claims. (Cl. 202—14)

1

This invention relates to an improved process and means for effecting the fluidized conversion and coking of relatively heavy petroleum charging stocks. More specifically, the improved process and means are provided for a continuous conversion of charging stocks such as topped crude, reduced crude, Bunker "C" fuel, and the like in a fluidized bed of solid particles to form more desirable lower boiling products and coke in the form of finely divided particles.

Various fluidized coking operations are known in the art which are continuous and of appreciable advantage over the earlier types of fixed bed coking, where a solid mass of coke deposit was allowed to build up on the walls of a coking chamber. However, the known fluidized coking operations generally utilize two or more separate contacting chambers and other devices for effecting the desired conversion reactions, the sizing of solid particles suitable for withdrawal as product or for further treatment, respectively, and the heating required for supplying the endothermic heat of the conversion reactions, while various ducts or conduits have been necessary to convey the particles from one chamber to another or to and from particle separating and grinding or sizing devices to permit a continuous operation.

It is a principal object of the present invention to provide a process for the continuous conversion and coking of relatively heavy petroleum stocks and similar high boiling or residual hydrocarbon materials wherein the solid particle mixture resulting from the conversion and coking reactions is segregated by differential settling in a fluidized bed into relatively heavy or coarse particles to be withdrawn as a product of the process upon drying or hardening, and into finer or lighter particles which are recirculated through the conversion and coking zone to permit the additional build-up of coke thereon.

Pursuant to this principal object the present invention provides for the conversion and coking of heavy hydrocarbon stocks of the aforesaid kind in a fluidized particle bed serving at the same time the effective performance of the conversion and coking reactions and the continuous segregation of relatively fine solid particles desired as nuclei for coke deposition from coarse particles desired as a product of the process. Thus the invention aims at obviating the segregation of nuclei for coke deposition by means of particle screening, grinding or other sizing devices which, due to their complicated structure and their arrangement outside the chamber con-

2

taining the coking zone, constitute the source of substantial heat losses and mechanical difficulties in a continuous flow system and require frequent inspection and repair in order that they may be maintained in working order.

Another important object of the present invention is to provide for the fluidized contacting of relatively heavy hydrocarbon stocks to effect the conversion and coking of the latter to desired products in a coking zone coordinated with adjacent and contiguous zones for the drying or hardening of the desired coke product and for the recirculation of fine particles, respectively, in a manner providing heat exchange between these zones and substantially eliminating a plurality of transfer conduits or pipes between these zones.

A further object of the invention is to provide the fluidized operation within a single confined 20 contacting chamber which is partitioned into the desired contacting zones adjacent to and in heat exchange relationship with one another in a manner to obtain maximum utilization of heat and a high conversion efficiency.

Still further, it is an object of the invention to provide an improved apparatus particularly suitable for performing the process herein described and having transfer means in the form of an open ended conduit in a substantially vertical and preferably central position to effect the recirculation of the finer subdivided particles, such that they are returned from an upper segregation zone in a straight line flow to the lower end portion of the coking and conversion zone.

Principally, the present invention provides an improved process for converting and coking a heavy hydrocarbon charge stream which comprises fluidizing finely divided solid particles by a gaseous heating and fluidizing medium in a bed ascending through a coking zone into a segregation zone openly communicating with the coking zone, introducing the charge stream into the lower portion of the fluidized bed within the 40 coking zone and converting it into lower boiling products and coke depositing on said particles during intimate contact with the heating and fluidizing medium, segregating resultant coarser from finer particles in the fluidized bed in the 45 segregation zone, discharging coarser particles continuously from the lower portion of the segregation zone into a confined driving zone and therethrough from the process, withdrawing finer particles continuously from the upper portion of 50 the fluidized bed in the segregation zone and re-

turning them in a confined dense phase stream to the lower portion of the coking zone and the fluidized bed therein, disengaging vaporous products upwardly from the fluidized bed and withdrawing them from the upper portion of the segregation zone.

In a specific embodiment the process of the present invention comprises passing a heavy hydrocarbon charge stream concurrently upwardly in a coking zone together with finely divided particles and a gaseous heating and fluidizing medium within an upwardly moving fluidized bed and therein effecting a high temperature conversion of the hydrocarbon charge stream to desired more valuable vaporous products and a coke deposition on the particles, discharging the fluidized bed comprising the resulting products and coked particles into a segregation zone above and openly contiguous with the coking zone, withdrawing the heavier coked particles from the lower portion of the segregation zone and passing them downwardly through a confined drying zone adjacent to and in indirect heat exchange relationship with the coking zone, withdrawing relatively fine coked particles from the top portion of the fluidized bed in the segregation zone and passing them in a relatively dense phase confined column extending downwardly through the coking zone to the lower portion thereof and recirculating them upwardly within the coking zone, discharging vaporous products from the upper portion of said segregation zone, and withdrawing excess coked particles from the lower portion of the drying zone.

In a preferred operation and arrangement of zones, the drying zone has an annular shape circumscribing the coking zone, such that a single confined chamber may be used to enclose the desired contacting zones. Also, the conduit withdrawing the finely divided particles from the upper portion of the segregation zone is preferably located concentrically within the coking zone such that the particles to be recirculated are brought in a confined straight line path to the lower end of the coking zone and distributed uniformly thereto. The finely divided particles which are first charged to the unit may be any inert material, but preferably are comprised of finely divided coke particles such that as coke is deposited on them and built up to provide larger particles they may be withdrawn from the unit in a continuous manner and provide a net production of usable coke material.

The particle separation in the segregation zone, which is maintained above the coking and drying zones, is brought about by reducing the rate of upward travel of the fluidized bed in the segregation zone and relative to that in the coking zone to such an extent that the simultaneous withdrawal of a separate stream of particles from each of the upper and lower portions of the fluidized bed in the segregation zone causes the heavier, coarser particles to settle at a greater rate than the finer particles and to travel downwardly while the finer particles are more strongly hindered by the gaseous and vaporous products ascending from the coking and drying zones from settling and are largely carried to the top portion of the fluidized bed wherefrom they are drawn into the open top end of the fine particles withdrawal conduit. The reduction of the rate of upward travel of the fluidized bed is attained by providing the segregation zone with a larger cross-sectional area than the coking zone, the enlargement exceeding substantially

the theoretically required enlargement for maintaining the rate of upward travel of the bed fluidized in the segregation zone by the gasiform materials ascending from both the coking zone and the drying zone equal to the rate of upward travel of the bed fluidized within the coking zone by the gasiform materials ascending in the latter. In the present process the linear upflow velocity of gasiform material is maintained substantially lower in the drying zone than in the coking zone, and also the volumetric rate of upward flow of gasiform material per unit weight of solid particles in contact therewith is materially less in the drying zone than in the coking zone. Consequently a substantial reduction in the rate of upward travel of the fluidized bed on passing from the coking zone into the segregation zone and a fairly satisfactory particle separation resulting thereby are attainable already when the cross-sectional area of the segregation zone is about equal to the sum of the cross-sectional areas of the coking zone and the drying zone. In the preferred embodiments of the present invention, however, a more drastic differential settling or more distinct particle separation is assured by providing the segregation zone with a cross-sectional area substantially larger than the combined cross-sectional area of the coking and drying zones.

The hot fluidizing and heating gas passing upwardly with the particles and hydrocarbon stream in the coking zone is preferably an inert stream, such as steam, and is supplied at a sufficient rate to maintain the desired fluidization and at a temperature sufficient for effecting the desired conversion and coking of the hydrocarbon stream in the presence of the subdivided particles. When such steam or other inert gas is utilized in the coking zone, this gasiform medium is preferably heated to the final high temperature outside of the confined chamber by means of combustion gases generated by burning coke or other less valuable combustible by-products of the process, or by other means as will be more fully explained hereinafter.

Pre-heating of the charge streams or at least a portion thereof may be effected through heat exchange relationship with resulting product streams. Thus, indirect heat exchange may be effected between the hydrocarbon charge stream and the gaseous and vaporous product stream from the upper portion of the segregation zone, while inert fluid for use as inert gaseous heating and fluidizing medium in the coking zone and/or as gasiform drying and aerating medium in the drying zone may be pre-heated by direct heat exchange with the hot net coke being withdrawn from the lower portion of the drying zone. Inert fluid, moreover may be pre-heated first by direct heat exchange with the hot net coke issuing from the drying zone and then by indirect heat exchange with the hot gasiform product stream issuing from the top portion of the segregation zone, the thus pre-heated inert fluid being then used as drying and aerating medium in the drying zone and in the fine particles withdrawal conduit. In the latter mode of heat utilization the partially cooled gasiform product stream may then be brought into direct or indirect heat exchange with the hydrocarbon charge stream to pre-heat the latter prior to fractionation of the former.

While previous types of fluidized coking units provide means for recirculating coke as nuclei to a conversion and coking zone, the present ar-

arrangement provides advantageous features over former arrangements in that the finer or less coarse particles are selectively withdrawn from the segregating zone by internal conduit means and in a manner which precludes loss of heat therefrom and redistributes them uniformly at the lower end of the coking zone. The heavier or coarser particles are in turn selectively passed to the drying zone and may be withdrawn therefrom in a manner which takes them out of the confined chamber, preventing their return to the coking zone. It is also an advantageous feature in the present operation to utilize gravity flow for the recirculation of the fine particles from the segregation zone to the coking zone, as well as gravity flow for the continuous withdrawal of the net product coke particles which are collected within the lower portion of the drying zone. Within this drying zone, the coke is freed from entrained or absorbed hydrocarbon vapors and transformed into hard particles of low volatile content by contact with an inert gaseous medium such as substantially oxygen-free flue gases or preferably steam at approximately the temperature prevailing within the coking zone.

The gasiform mixture which is discharged from the upper portion of the segregation zone is passed to suitable separating and fractionating equipment. However, in a preferred mode of carrying out the present invention, this gasiform product stream is passed in heat exchange relationship with the hydrocarbon charge stream, or alternatively, in heat exchange with at least a portion of the charge streams being passed to the lower portion of the drying and aerating gas distribution nozzles which in turn are utilized to distribute drying or devolatilizing gases uniformly to the annular shaped drying zone. The use of a single confined chamber to enclose the essential contacting zones is of course economical from the standpoint of simplicity, relative to the use of a plurality of separate contacting chambers and supports or superstructures therefor, and in addition effects the elimination of long transfer conduits between separated zones.

Reference to the accompanying drawing and the following description thereof will serve to more clearly point out the operation of a preferred embodiment, as well as indicate or clarify various features and advantages obtained by the present fluidized operation.

Referring now to the drawing, there is shown a vertically disposed and confined chamber 1, having the upper portion thereof somewhat enlarged in diameter and providing a particle segregation section 2. Within the lower elongated portion of the chamber and spaced from the outer wall is a cylindrical baffle or partition 3, which in turn separates the lower portion of the unit into an annular shaped particle drying section 4 and a coking section 5. The baffle member 3 forms a seal between the lower portions of the drying section and the coking section. The lower portion of the baffle member 3 is of somewhat smaller diameter and is indicated in this drawing to extend somewhat below the lower head of the external chamber 1, in order to provide a suitable inlet section 6 at the lower end of the coking zone. Positioned centrally within and vertically through the coking zone and extending downwardly into the inlet section 6, is an open-ended conduit or particle return leg 7 having its open upper extremity extending above the partitioning wall 3, in a manner suitable to permit the withdrawal of the finer or lighter coke particles which are

carried to the upper portion of the particle segregation zone 2. As hereinafter discussed more fully in connection with the operation of the unit, the conduit 7 provides for the continuous recirculation of the finer particles within the unit into the inlet end of the coking zone. Also, as has been noted, finely divided coke particles are preferably charged to the unit initially to provide the necessary nuclei for aiding in the conversion of and coke deposition from a relatively heavy hydrocarbon charge stream, new nuclei being thereafter formed by the coking reactions in addition to the deposition of coke on particles already present.

The hydrocarbon charge stream is introduced into the lower end of the coking zone by means of inlet line 8, having control valve 9, and suitable distributing means 10 effecting the substantially uniform introduction of the material into the lower end of the zone and into contact with the upwardly flowing particles. As hereinbefore noted, the hydrocarbon charge stream may be a relatively heavy material such as Bunker "C" fuel, topped crude, reduced crude, heavy tar, asphaltic residue, or the like, which is normally liquid or liquefiable at moderate temperatures up to about 250° F. The charge stream is preferably preheated to a temperature of from about 500° to about 700° F. or generally to a temperature below active coking temperature and may thus be more or less vaporized prior to introduction into the coking zone for conversion into desired gasiform cracked products and coke deposition on the particles. A gasiform heating medium suitable to supply the endothermic heat requirements within the coking and conversion zone is supplied through line 11, having valve 12, and is distributed uniformly within the inlet section 6 by a distributor 13. The latter operates also to uniformly fluidize and aid in the circulation of the particles descending through the recirculating leg 7 to the lower end of the coking zone. The preferred heating and fluidizing medium introduced to this zone by way of line 11 is a high temperature inert gas or steam at about 1000° F.-1200° F. or more, which has been heated in a zone external of the conversion zone 5 and chamber 1 and which maintains the fluidized bed at active coking temperature, usually within the range of from about 850° to 1000° F. The heating of the fluidizing and heat supplying medium to the desired elevated temperature preferably is effected outside of the chamber 1 by the combustion of low value by-products of the process, or of a portion of the coke produced. Alternatively, heat may be generated in the coking and conversion zone itself by the introduction of an oxygen containing gas, such as air or a gas having a higher or lower free oxygen content than air, such that a controlled portion of the combustible materials present in the fluidized bed in the coking zone may be burned to supply the endothermic heat requirements within this zone and maintain the ascending fluidized bed therein at active coking temperature.

Sufficient reactant charge and heating gas is supplied to the chamber to maintain fluidization therein at a level, as indicated by the broken line 14, which is above the upper extremity of the fine particles return leg 7. However, the fluidization is coordinated with respect to the size and cross-sectional area of the conversion, drying and particle segregating zones, such that the velocity of the particles is reduced in the latter zone to permit substantially only the finer particles to be

carried to the upper level of the relatively dense phase fluidized bed and thus be subject to recirculation downwardly through the conduit 7. Some aerating gas may be supplied through line 41 and valve 42 to pass into the return leg 7 in order to prevent clogging or undue compacting of the particles as they descend in the leg. In a preferred operation the fine particles are permitted to flow downwardly by gravity in a relatively compact column confined by a relatively small diameter straight conduit being placed concentrically within the coking zone.

The resulting conversion gases and vapors are continuously withdrawn from the upper portion of the segregation zone 2 by way of a suitable particle separating apparatus 15, connecting with a suitable outlet line 17 having control valve 18, and recovered particles are returned to the return leg 7 through dip leg 16. In accordance with the preferred operation of the unit, the gasiform product stream passes through heat exchange means 19 and is subsequently discharged through conduit 20 which carries the stream to suitable fractionating and separating equipment. Steam or other substantially inert gasiform medium may be passed through line 21 having control valve 22, and through the heat exchanger 19, to be subsequently passed to the lower end of the drying section by way of lines 23 and 24, having respectively valves 25 and 26, with suitable distributing rings or headers 27 and 28 arranged to uniformly introduce the medium into the annular zone. The drying and aerating gas passing to this zone need not be at a high temperature, with respect to the coking and conversion zone, for sufficient heat is transferred by heat exchange within the chamber 1 from the coking zone to the drying zone to maintain in the latter a temperature of the order of 750° to 950° E. which is in general sufficient to devolatilize the coarse coke particles descending in this drying zone and provide a desire form of hard, granular coke that may be withdrawn from the unit.

Although excess coke particles which are accumulated in and withdrawn from the lower end of the chamber 1 may be used as moisture-free particulated coke, it is economically desirable to pass the coke particles downwardly by way of line 29 and control valve 30 to the interior of a quenching and steam generating chamber 31, whereby heat may be withdrawn from the discharged particle stream for use within the unit. A suitable quenching medium such as water is introduced into the lower portion of the chamber 31 by way of line 32 and control valve 33 so as to countercurrently contact the descending bed of coke particles and effect simultaneously the cooling of the latter and the generation of low temperature steam within the unit. Resulting steam is withdrawn through a suitable particle separator 34 and outlet line 35, while resulting cooled coke particles may be withdrawn from the lower portion of the quenching and steam generating chamber by means of an outlet line 36 and control valve 37. Another advantage of the water cooling is that the coke material may be withdrawn from the cooling chamber in a slurry stream.

The steam discharged by way of line 35 may be passed to a suitable steam collecting drum for use in the processing plant, with flow regulated by control valve 38. However, in accordance with the preferable operation of the present coking and conversion unit, at least a part of the steam is utilized to provide heating steam, 75

or drying and aerating steam within the drying zone. The low temperature steam is passed by way of the transfer line 39 and control valve 40 to line 21 and via the latter conduit through the heat exchanger 19 for an increase in temperature and subsequent distribution through conduit 23.

It may also be noted that a portion of the generated steam, or other externally supplied drying and aerating gas is passed through line 23 and may be distributed, by way of line 41 and control valve 42, into the lower end of the coking and conversion section, at the inlet section 6, in order to provide additional aerating medium in that section as well as to provide means for aerating the material descending in the return leg 7.

The coking operation of the present embodiment may be carried out at any desired sub-atmospheric, substantially atmospheric, or super-atmospheric pressure. It is preferable to operate the unit at a low superatmospheric pressure, of the order of 10 to 75 pounds per square inch, which is sufficient to permit the fractionation of the gasiform product stream at above atmospheric pressures.

In order to obtain desirable operating conditions, it is also necessary to coordinate and regulate the cross-sectional area of the various particle passage ways and contacting zones. The free cross-sectional area of the conversion and coking zone 5 is intermediate to the free cross-sectional areas of the segregation zone 2 and the drying zone 4, and preferably the cross-sectional area of the segregation zone is larger than the combined cross-sectional areas of the coking and drying zones, with the coking zone being of the order of about twice the cross-sectional area of that of the drying zone. These proportions permit the proper intense fluidization within the coking zone relative to a less intense fluidization within the segregation zone, the fine particles return leg, and the drying zone. A relatively dense moving contact bed of material may be accommodated in the drying zone. Thus, the density of the fluidized bed within the coking zone is always maintained appreciably lower than the densities of the descending masses within the particle return leg 7 and within the annular column of material in the drying zone 4. Although the accompanying drawing in a general way indicates a preferred relation between the diameters of the principal contacting zones, this drawing is not to scale, and it is to be understood that the arrangement and proportion of zones which is shown are not to be considered limiting.

The present operation and arrangement of zones, while particularly advantageous for the coking and conversion of relatively heavy fuels, need not be limited to that use only, for other processing operations which may be carried out in a fluidized manner may well make use of the compact arrangement of zones and the economical manner of flow. However, coke which is produced in a manner as has been described provides a substantially pure form of coke which is desirable as a metallurgical coke, or alternately as a coke for the manufacture of electrode carbon. The hydrocarbon vapor products may be recovered from the fractionation section as lower boiling more valuable products, or as a desirable form of charging stock for a catalytic cracking or other hydrocarbon conversion operation.

I claim as my invention:

1. A process for converting and coking a heavy

hydrocarbon charge stream which comprises fluidizing finely divided solid particles by a gaseous heating and fluidizing medium in a continuous bed ascending through a coking zone into a segregation zone openly communicating with said coking zone, introducing said charge stream into the lower portion of the fluidized bed within said coking zone and converting it into lower boiling products and coke depositing on said particles during intimate contact with said heating and fluidizing medium, reducing the rate of upward travel of said fluidized bed in the segregation zone and segregating resultant coarser from finer particles in the fluidized bed in said segregation zone, discharging coarser particles continuously from the lower portion of said segregation zone into a confined drying zone and therethrough from the process, withdrawing finer particles continuously from the upper portion of the fluidized bed in said segregation zone and returning them in a downwardly moving confined dense phase stream to the lower portion of the coking zone and the fluidized bed therein, and disengaging vaporous products upwardly from said fluidized bed and withdrawing them from the upper portion of said segregation zone.

2. A process for converting and coking a heavy hydrocarbon charge stream which comprises fluidizing finely divided solid particles by a gaseous heating and fluidizing medium in a continuous bed ascending through a coking zone into a segregation zone openly communicating with said coking zone, introducing said charge stream into the lower portion of the fluidized bed within said coking zone and converting it into lower boiling products and coke depositing on said particles during intimate contact with said heating and fluidizing medium in said coking zone, reducing the rate of upward travel of said fluidized bed in the segregation zone and segregating coarser from finer particles in the fluidized bed in said segregation zone, passing coarser particles continuously from the lower portion of said segregation zone into and through a confined drying zone adjacent to and in indirect heat exchange relationship with said coking zone, recovering a stream of said coarser particles from said drying zone as a product of the process, withdrawing finer particles from the upper portion of the fluidized bed in said segregation zone and returning them in a downwardly moving confined dense phase stream to the lower portion of the coking zone and the fluidized bed therein, and disengaging vaporous products upwardly from said fluidized bed and withdrawing them from the upper portion of said segregation zone.

3. A process for converting and coking a heavy hydrocarbon charge stream which comprises fluidizing finely divided solid particles by a gaseous heating and fluidizing medium in a continuous bed ascending through a coking zone into a segregation zone openly communicating with said coking zone, introducing said charge stream into the lower portion of the fluidized bed within said coking zone and converting it into lower boiling products and coke depositing on said particles during intimate contact with said heating and fluidizing medium in said coking zone, reducing the rate of upward travel of said fluidized bed in the segregation zone and segregating resultant coarser from finer particles in the fluidized bed in said segregation zone, discharging coarser particles continuously from the lower portion of said segregation zone into a confined drying zone and therethrough from the process, with-

drawing finer particles continuously from the upper portion of the fluidized bed in said segregation zone and passing them in a dense phase stream through a confined path extending downwardly through said fluidized bed to the lower portion of the coking zone, discharging said dense phase stream from said confined path into the fluidized bed ascending in said coking zone, and disengaging vaporous products upwardly from said fluidized bed and withdrawing them from the upper portion of said segregation zone.

4. A process for converting and coking a heavy hydrocarbon charge stream which comprises, passing said stream concurrently upwardly in a coking zone together with finely divided particles and a gaseous heating and fluidizing medium within an upwardly moving fluidized contacting bed and therein effecting a high temperature conversion of said hydrocarbon charge stream to desired vaporous products and a deposition of coke on said particles, discharging the fluidized bed comprising the resulting products and coked particles into a segregation zone above and openly contiguous with said coking zone, withdrawing the heavier coked particles from the lower portion of said segregation zone and passing them downwardly through a confined drying zone adjacent to and in indirect heat exchange relationship with said coking zone, withdrawing relatively fine coked particles from the top portion of said bed within said segregation zone and passing them in a relatively dense phase confined column extending downwardly through said coking zone to the lower portion thereof and recirculating them upwardly within said coking zone, discharging vaporous products from the upper portion of said segregation zone, and withdrawing excess coked particles from the lower portion of said drying zone.

40 5. The method of claim 4 further characterized in that said fine particles withdrawn from said segregation zone are passed in a straight line confined column to the lower end of said coking zone for recirculation therethrough.

45 6. A method for converting a relatively heavy hydrocarbon charge stream into lower boiling products and coke which comprises, dispersing said stream concurrently upwardly in a coking zone with finely divided coke particles and a gaseous heat supplying and fluidizing medium within a continuous fluidized contacting bed extending through said coking zone into a segregation zone maintained above and openly contiguous with said coking zone, converting the dispersed charge stream into lower boiling gasiform products and a deposition of coke on the particles within said fluidized bed, withdrawing the heavier coked particles from the lower portion of said segregation zone and passing them downwardly in an annular column through a confined drying zone maintained adjacent to and concentrically around said coking zone and in indirect heat exchange relationship therewith, withdrawing finely divided lighter coked particles from an upper portion of said bed within said segregation zone and passing them in a relatively dense phase confined straight line column downwardly through said coking zone to the lower portion thereof and recirculating them upwardly in said coking zone in a continuous manner with said hydrocarbon charge stream and said gaseous heat supplying and fluidizing medium, discharging vaporous and gaseous products from the upper portion of said segregation zone, introducing a drying and aerating gas stream to the lower portion of said an-

nular drying zone to countercurrently contact the descending heavier coked particles therein, and continuously withdrawing excess coked particles from the lower portion of said drying zone.

7. The method of claim 6 further characterized in that said heat supplying and fluidizing medium comprises high temperature steam.

8. The method of claim 6 further characterized in that said heat supplying and fluidizing medium comprises a stream containing free oxygen.

9. The method of claim 6 further characterized in that at least a portion of the drying and aerating gas stream being introduced into the lower portion of said drying zone is first passed in indirect heat exchange relationship with the hot product stream being discharged from the upper portion of said segregation zone, and said gaseous heat supplying and fluidizing medium introduced into the lower portion of said coking zone comprises a hot inert gaseous medium heated within heating means external to said coking zone.

10. The method of claim 9 further characterized in that said coked particles being withdrawn from the lower portion of said drying zone are continuously discharged into a separately confined steam generating zone wherein said particles are countercurrently contacted with an aqueous liquid whereby to generate steam, at least a portion of said generated steam is passed in heat exchange with said product stream, and resultant high temperature steam is introduced as drying an aerating gas into the lower portion of said drying zone.

11. A unitary apparatus suitable for effecting fluidized conversion and coking of a heavy hydrocarbon stream in the presence of finely divided solid particles, which comprises in combination, a confined vertically disposed contacting chamber having a partition positioned concentrically within the lower portion thereof and forming an internal contacting section and an external annular shaped contacting section, a particle segregation section within the upper portion of said chamber above and openly contiguous with each of said contacting sections, a vertically positioned open-ended conduit having its upper end extending above the upper extremity of said partition with the lower end of said conduit terminating within the lower portion of said internal contacting section, a gas outlet from the upper portion of said segregation section, fluid inlet means at the lower end of each of said contacting sections, and particle outlet means from the lower portion of said external section.

12. A unitary apparatus suitable for effecting fluidized conversion and coking of a relatively heavy hydrocarbon stream in the presence of finely divided solid particles, which comprises in combination, a confined cylindrical and vertically disposed contacting chamber having a circular partition member positioned concentrically within the lower portion thereof and forming an internal contacting section and an external contacting section, and an enlarged cross-sectional area particle segregation section within the upper portion of said chamber above and openly contiguous with each of said contacting sections, a vertically positioned open-ended conduit placed concentrically within said internal contacting section, said open-ended conduit having its upper extremity extending above the upper end of said circular

partition and the lower end of said open-ended conduit terminating within the lower portion of said internal contacting section and adapted for recirculation of fine particles from the upper portion of a fluidized bed maintained within said chamber downwardly to the lower end thereof, a product gas outlet from the upper portion of said segregation section, fluid inlet and distributing means at the lower end of each of said internal and external contacting sections, said distributing means being arranged to uniformly distribute fluid to each of said contacting sections, and particle outlet means from the lower portion of said annular shaped external section suitable for the continuous withdrawal of particles from said chamber.

13. The apparatus of claim 12 further characterized in that said internal contacting section has a greater cross-sectional area than said external annular shaped section, and said segregation section has a greater cross-sectional area than the combined cross-sectional areas of the internal and annular shaped external contacting sections.

14. The apparatus of claim 12 further characterized in that a particle separating means connects with said product gas outlet, and a particle return conduit extends from said particle separating means into the upper portion of said open-ended conduit for the recirculation of fine particles to the lower end of said internal contacting section.

15. The apparatus of claim 12 further characterized in that heat exchange and conduit means connect with said product gas outlet and with said fluid inlet means at the lower end of said contacting sections to provide heat exchange between fluid to be introduced to the latter and a gasiform product stream removed from the upper portion of said segregation section.

16. The apparatus of claim 15 further characterized in that said particle outlet conduit from the lower portion of said external contacting section connects with a particle quenching chamber, a fluid inlet connects with the lower end of said quenching chamber in a manner permitting the countercurrent contact of hot particles passing downwardly through said chamber, an outlet for gasiform material from the upper portion of said quenching chamber connects with said heat exchange means for said gasiform product stream from the upper portion of said segregation section, and conduit means from said heat exchanger connects with the lower ends of each of said internal and external contacting sections to permit supplying a heated aerating medium thereto.
